(57) **CLAIM**

The ornamental design for a rawhide treat for dogs as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a rawhide treat for dogs showing my new design;

FIG. 2 is a rear elevational view thereof;

FIG. 3 is a left side view thereof;

FIG. 4 is a right side view thereof;

FIG. 5 is a perspective view thereof;

FIG. 6 is a second perspective view thereof;

FIG. 7 is a third perspective view thereof; and,

FIG. 8 is a fourth perspective view thereof.
